TITANIUM-BASE ALLOYS

Robert I. Jaffee, Horace R. Ogden, and Daniel J. Maykuth, Columbus, Ohio, assignors, by mesne assignments, to Remington Arms Company, Inc., Bridgeport, Conn., a corporation of Delaware

No Drawing. Application March 2, 1951, Serial No. 213,689

7 Claims. (Cl. 75—134)

1

This invention relates to titanium-base alloys, and particularly to ternary alloys of titanium and aluminum with bismuth.

The use of titanium as a structural material is limited by its relatively low strength and high cost, and it becomes desirable to alloy titanium with such other metals as will increase the strength to acceptable levels and preferably at the same time effect some reduction in the total material cost. Aluminum is a metal well suited to the attainment of these objectives, being low in weight, relatively low cost, and having a material strengthening effect on titanium. However, the amount of aluminum alone that can be added to titanium is limited by its adverse effect on ductility. Binary alloys of titanium with more than about 5% of aluminum are too brittle for most structural uses; and such binary alloys containing less than about 5% of aluminum do not possess sufficient strength to be of general utility. A further strengthening is highly desirable.

The present invention comprises the discovery that the addition to titanium-aluminum alloys of 0.5% to about 5% of bismuth effects a marked improvement in the properties of titanium-aluminum alloys of a given aluminum content, say 3.5% to 5%. The alloys show a rare combination of extraordinary strength with adequate ductility, notwithstanding the loss of some bismuth in melting.

The metal used as a base for the alloys of the present invention may contain the interstitial contaminants, carbon, oxygen and/or nitrogen, up to at least the total quantity to be found in good quality commercial titanium. Carbon, for example, has been found to be beneficial when present in amounts between 0.02% and 0.3%, the latter being about the maximum amount which is soluble in alpha titanium. An excess of carbon tends to form embrittling carbides. For a typical alloy, a carbon content of 0.1% to 0.2% is desirable, but the optimum amount varies with other factors. Nitrogen is a potent hardener of

titanium and may be added in amounts up to 0.5% without appreciable loss of ductility. Oxygen and nitrogen are deleterious to titanium and tend to reduce its ductility and strength.

It is an object of this invention to provide an alloy of titanium, aluminum and bismuth which is

stronger and more ductile than the corresponding binary alloys.

It is another object of this invention to provide an alloy of titanium, aluminum and bismuth which is

stronger and more ductile than the corresponding binary alloys.

It is a further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

It is a still further object of this invention to provide an alloy of titanium, aluminum and bismuth which is

stronger and more ductile than the corresponding binary alloys.

Intended Composition (Balance Titanium)			Tensile Properties—p. s. i.					
Al	Bi	C	V. H. N. Surface	Proportional Limit	0.2% Offset Yield	Ultimate Strength	Elongation in 1"	Bend T
5	0.5	0.25	391	110,000	121,000	123,000	20	1.8
5	1.0	0.25	403	108,000	125,000	128,000	18	2.6
5	1.5	0.25	416	99,000	124,000	130,000	18	5.1
5	2.5	0.25	356	102,000	124,000	128,000	17	5.4
5	5.0	0.25	396	105,000	136,000	137,000	3	7.1

In the foregoing tabulations "bend ductility" is the radius, expressed as a multiple of specimen thickness, to which the specimen can be bent to an angle of 75° without fracture.

It will be seen that the addition of as little as 0.5% of bismuth substantially increases the strength of the titanium-5% aluminum alloy, with no loss of ductility. Increasing the bismuth addition to 2.5% tends to produce a further increase in strength, the loss in ductility being slight. With a bismuth addition of 5%, strength has increased materially and enough ductility remains to meet the requirements of a wide variety of uses. Due to relatively small differences between yield and ultimate strengths, the alloys find their greatest utility for uses in which the material is not stretched during fabrication.

What is claimed is:

1. An alloy consisting essentially of from 3.5% to 5% aluminum, from 0.5% to 5% bismuth, from 0.02% to 0.3% carbon, balance titanium. 20
2. An alloy consisting essentially of about 5%

aluminum, from 0.5% to 5% bismuth, from 0.02% to 0.3% carbon, balance titanium.

3. An alloy consisting essentially of about 5% aluminum, from 0.5% to 5% bismuth, from 0.1% to 0.25% carbon, balance titanium.

4. An alloy consisting essentially of about 5% aluminum, from 0.5% to 2.5% bismuth, from 0.1% to 0.25% carbon, balance titanium.

5. An alloy consisting essentially of about 5% aluminum, 0.5% bismuth, from 0.1% to 0.25% carbon, balance titanium.

6. An alloy consisting essentially of about 5% aluminum, 1.0% bismuth, from 0.1% to 0.25% carbon, balance titanium.

10 7. An alloy consisting essentially of about 5% aluminum, 2.5% bismuth, from 0.1% to 0.25% carbon, balance titanium.
